UNITED STATES PATENT OFFICE

SAMUEL G. THOMSON, OF FLUSHING, NEW YORK

RAILWAY RAIL AND RAIL JOINT

Application filed May 6, 1930. Serial No. 450,112.

This invention relates to a novel distribution of metal in the rail foot and in the upper portion of the rail web adjacent to its juncture with the rail head. This effects economies in manufacture and in metal distribution. It provides also, a rail and a splice bar of better design and stability in service.

This application is supplementary to my application No. 442,948, filed April 9th, 1930, and also to my application No. 445,264, filed April 18th, 1930. This invention applies particularly to the designs of aforesaid applications which have an enlarged concave or flat face gradually extending upwardly and outwardly from the rail web to the under corner of its head. Some of these designs are made practicable only by providing a special form of lower bearing on the rail foot such as will counteract the tendency of the bar to slide upwardly and outwardly away from the rail head under load and the clamping action of the bolts. Such a special foot bearing, in combination with upper rail sections and bearings for the bar similar to some of those shown in aforesaid applications, is the subject matter for this application.

Among the advantages enumerated in aforesaid applications which apply with equal force here, may be mentioned the benefits in rail manufacture as outlined in application No. 442,948. The use of gradually slanting faces to eliminate the abrupt change in section at the juncture of the rail web with its head, together with the increased stability attained for the splice bar and the larger area for its upper bearing, should be considered to be a valuable advance in the art. In addition to the advantages which are common to these several applications, some others are particularly applicable to the "two-inclination" top surface of the rail foot, which best may be understood by following the description of the various figures of the drawings, to follow.

The "pear head" was a familiar shape in the early development of the railway rail; but the downwardly and inwardly sloping sides were not used as bearings for splice bars. These sloping sides, however, were used as bearings in some of the early types of the

"bull head" and "double head" rails. In the early development of the T-rail with its wide flat base, the desire to carry the rail load through the joint by the stiffness and strength of the splice bars which up to that time were 55 only used to hold the rail ends together, brought about sharp offsets in the rail section at the juncture of the rail web with the rail head and foot. The result was, that the inclination of the fishing or bearing angles 60 was flattened out to correspond to the laterally extending foot, and in order to obtain a more nearly horizontal position for the upper bearing as an aid in carrying the load more directly under the rail head. A one-to-four 65 inclination—about 14 degrees with the horizontal—was and has since been used as the prevailing practice, with the extreme cases ranging from 11 to 14 degrees for the bearing on top of the rail foot, and 11 to 18 and even 70 20 degrees for the upper bearing under the rail head, 23 degrees being used in one design in 1874.

A further desire to widen the rail base without the use of too much metal in the 75 rail foot, has resulted in a further flattening out of the top surface of the rail foot adjacent to its outer edge to an inclination as close to the horizontal as one-to-fifteen, a recent practice in France. This rail used in France 80 with its top surface of the foot comprising two faces inclined at different angles, has some of the characteristics of my invention; but the former art in this respect has been with the view of widening the bottom of the 85 rail to provide a better bearing area on the ties; also to increase the rail stiffness and to diminish its tendency to turn over or to draw the track fastenings in service. No relationship has heretofore been claimed between the double inclination of the upper 90 surface of the rail foot and a special design of upper bearing for the bar under the rail head. The novelty of my invention consists in the use of one of these differently inclined 95 faces at an inclination greater than heretofore suggested, in order to balance or counteract an extra inclination of the upper bearing of the bar against the rail head under service loads and the pull of the bolts. This 100 105

use of extra inclination of a portion of the rail foot in combination with an enlargement of the upper part of the rail web adjacent to its juncture with the rail head comprise the basic idea of my invention.

The novelty of my improvement is all the more apparent as the enlarged upper section of the rail web results in a design which approaches the shape of the old "pear head" rail; since no attempt has been made heretofore to use load-carrying splice bars against the widely and gradually spreading sides of this type of rail. In order to accomplish this, it is obvious that a lower bearing with an opposite inclination is necessary, the amount of inclination required depending upon the relative location and the conformation of the upper bearing and particularly the upper portion of the upper bearing when it is a curved surface.

The enlarged upper bearing with its greater inclination under the rail head, which is one of the characteristics of my improvement, heretofore has not been practicable on account of the tendency for the top of the bar to slip upwardly and away from the rail head under load and the tension of the bolts. In illustrating the means provided for balancing this tendency to slip, I have used in most of the figures of the drawings inclinations and curves of these bearings such as will cause a slight tendency for the top of the bar to move inwardly. In this connection, it will be noted by comparing the various figures of the drawings, that there are two basic factors in the lower bearing of the bar that are used to govern the tendency at the top of the bar to move inwardly or outwardly. These two factors are: the steep inclination of the bearing, and its inward or outward location with reference to the upper bearing. The steep inclination in itself when located directly under the upper bearing is not sufficient to neutralize a slight tendency for the top of the bar to move outwardly, as may be noted in three of the figures; but when the steeply inclined bearing is located on the outer portion of the rail foot as in the other figures, then the tendency is for the top of the bar to move inwardly.

The graphic representation of forces shown diagrammatically in connection with the various figures of the drawings is only approximate for illustration of the principles involved; and it may be understood from the following description in detail of the various designs of rails and splice bars supplemented by the graphic representation of the acting forces, that in most cases only slight changes in curvature, inclination and relationship of the upper and lower bearings of these designs are necessary in order to afford a balanced condition in the clamping action of the bar against the rail.

The precise nature, novelty and combina-

tions of these various features of my invention may best be understood by reference to the accompanying drawings, in which I have illustrated a number of the more desirable forms and combinations which my improvement may take. It is presumed, however, that the invention is susceptible of various other modifications without departing from its spirit and scope as defined in the appended claims.

Figures 1 to 8 inclusive, are sectional elevations of a rail and a splice bar showing some of the preferable forms of my invention, the various details and combinations of which may best be understood from the description of each figure to follow.

Similar reference characters designate corresponding parts throughout the various figures of the drawings.

The letter H, whenever seen, designates the rail head; W, the rail web; F, the rail foot; B, the splice bar; C, the upper bearing of the splice bar against the rail; D, the lower bearing of the bar against the rail; E, a portion of the upper surface of the rail foot free of contact with the splice bar, and at an inclination different from D; G, a concave face in the fillet joining the upper surface of the rail foot with the rail web; line a—a through the abutments of the upper and the lower bearings of the bar against the rail indicates the relative location of these two bearings; line b—b indicates the bisector of the angle which the plane of the upper bearing makes with the plane of the lower bearing; line f—f indicates the component force of the bolt-pull perpendicular to abutment line a—a.

Figure 1 shows a rail having a shallow and steeply inclined uniform curved face C joining the rail web to the under corner of the rail head. This changes the rail section gradually and continuously from the width or thickness of its web to the width of its head. Bearing D, on the outer portion of the rail foot, has a much greater inclination than another portion E, which in turn, is joined to the rail web by a concave fillet-face G.

The location of bearing D on the outer portion of the rail foot, gives considerable inclination to the line a—a through the outer portions of the upper and the lower bearings. This "abutment line" is used to indicate the relative location or position of one bearing under the other. The outer location of bearing D is effective in increasing the tendency of the top of the bar to move inwardly under the vibration and wear of track service, and the steep inclination of bearing D is effective in causing the same tendency, in that it neutralizes or partly opposes the steep inclination in the opposite direction at the upper bearing, thus reducing the tendency of the top of the bar to move outwardly.

In order to indicate graphically some of

these relationships, diagrams are shown in connection with each figure of the drawings, all of which may be understood in the same way as described for this Figure 1, as follows:

A line through the upper and the lower edges 1 and 2 of bearing C indicates approximately the direction that the head of the bar tends to slide in either direction. This line 10 happens to make about a 90 degree angle 3, with the surface of bearing D projected, and about a 60 degree angle 4, with surface E projected. The bisectors of these angles are respectively, lines $b-b$ and $b'-b'$. Components of the bolt-clamping force perpendicular to abutment line $a-a$ are indicated by line $f-f$ for angle 3, and by line $f'-f'$ for angle 4. These components intersect the bisectors of these angles at the rail web which is taken 20 as a point of convenience. As the bar is guided into the angle made by the inclinations of its upper and lower bearings, its reaction or tendency toward rotation is indicated as acting outwardly along the line of 25 the bisector. By choosing a convenient length from the point of intersection of the bisector with the component of the inwardly acting force, the third side of the triangle may be drawn parallel to the abutment line 30 $a-a$ to represent the tendency of the bar to rotate in its bearings under wear and service conditions. When different designs and angles for the bearings are compared, the relative lengths of the third sides of the 35 resulting triangles are approximately proportional to the magnitude of the tendencies of the bars to slip around in their bearings, and the direction of the slip is indicated by arrows. By comparing in this way the bar 40 shown in Fig. 1 having the steeply inclined outer bearing D with a bar not shown but having its lower bearing with the lesser inclination of face E, it will be noted that the two bars will be drawn into the angles 3 and 45 4 respectively, with the result, as indicated by symbols $f-b$ and $f'-b'$ representing the third side of the corresponding triangles, that angle 3 would tend to cause a rotation of the bar inwardly at the top to the position shown in the drawing by long-dotted lines, while angle 4 would 50 tend to cause rotation of the bar outwardly at the top to the position shown by short-dotted lines. These symbols also show by their comparative lengths that the tendency 55 inward toward the long-dotted position is the greater.

Figure 2 shows a rail having a flat face C for the upper bearing instead of the shallow curved face shown in Fig. 1, the general inclinations of the two faces being about the same. In this design, the upper edge of the bearing of the bar, indicated by a vertical line at a , lies considerably inside of a vertical plane at the outer edge of the rail head,

and the side face of the rail head is cut under by a large radius almost to the upper edge of this bearing. The lower bearing D is steeply inclined and comprises the inner portion of the rail foot, so that abutment line 70 $a-a$ is vertical. In order to compare this arrangement with a similar bar having its lower bearing on a rail foot with the usual 14 degree inclination, the lower bearing D may be considered as cut away from the rail 75 to form a rail foot as shown by dotted line at 5. With the bearing faces projected to form angles 6 and 7, it will be noted from the graphic symbols that, in both designs— 80 with and without the steep lower bearing—the tendency of the bar is to rotate outwardly at the top to the position shown in dotted lines. Symbol $b'-f'$ indicates that this rotating tendency is excessive with the usual 85 fishing-angle inclination on top of the rail foot. In such an arrangement, the bar would very soon pull up against the rail web below, as indicated in dotted position of the bar. Symbol $b-f$ shows almost a balanced condition, with the steeply sloping lower bearing D, whatever tendency there is for the top 90 of the bar to move outwardly being slight. When this condition as represented by symbol $b-f$ is compared to that represented by $f-b$ in Fig. 1, where the tendency at the 95 top of the bar is rather strongly inward, a very clear indication is shown of the effect of the inner and the outer locations of the lower bearing, the inclinations at the top and bottom bearings being similar in both figures. 100

Figure 3 shows a rail with an extra wide head and with a deep regularly curved face extending downwardly and inwardly from the under corner of the wide head to a point of tangency 8 with the upright face of the 105 rail web. This gives a gradual increase of the enlarged upper portion of the web without any abrupt offsets in its section. By using a very small radius for the under corner of the rail head, the upper bearing for 110 the bar is carried well over almost to a horizontal position at 9, which when combined with the deepness of the curved face, gives a very solidly anchored bearing at the top. This assists in holding the bar against its 115 tendency to rotate in its bearings. The head bearing of the bar is carried down around the curve to 10, which with the wide rail head affords an exceptionally wide upper bearing area. Bearing D approaches the usual 14 degree inclination, which is much less than the 120 steep inclinations shown in the former figures. This bearing D occupies the outer portion of the rail foot, which foot is shown with unusual width. The free upper surface 125 E of the foot is convex, and it approaches a horizontal position as it joins with fillet-face G. Symbol $f-b$ indicates that the bar has a rather strong tendency to slide inwardly at the top. This is somewhat counteracted 130

by carrying the upper bearing of the bar down around the curve toward the rail web.

In Figure 4, the enlarged upper portion of the rail web is increased upwardly more gradually than in Fig. 3 by means of a parabolic bearing surface C. This increases the curvature of the bearing rapidly as it approaches almost to a horizontal position 11 at its top. This design again shows a very gradual increase in the web thickness throughout the entire height of this zone adjacent to the rail head. It will be noted from the symbol $b-f$, that the bar has a slight tendency outward at the top, which is neutralized somewhat by the wide lateral overhang of the rail head at 11.

The substantially horizontal position of the uppermost portion of the under surface of the rail head as shown in Figs. 3 and 4, is not essential to this invention, but may be used in combination with the basic features of this invention to provide some of the most desirable and practical forms. This substantially horizontal position of the upper portion of the bearing, therefore, is not claimed specifically in this application, but is made the subject matter and claimed broadly in a separate application, Serial No. 454,575, filed May 22nd, 1930.

It will be noted in Fig. 4, that bearing D is located on the inner portion of the rail foot directly under the upper bearing, and that its angle of inclination is intermediate between the extremely steep inclinations shown in Figs. 1 and 2, and the inclination of usual practice shown approximately in Fig. 3. With these lower bearings having the lesser inclinations, and particularly when the bearing forms the inner portion of the surface 40 of the rail foot, the tendency of the bar is to swing in at the bottom around the upper bearing as a fulcrum, rather than for the entire bar to rotate around its own centre,—inwardly at the bottom and outwardly at the top. In these designs as shown in Figs. 3 and 4, where there is a combination of the fulcrum or swinging motion and the rotating motion, the result is an upward and inward thrust with a slight slipping in the upper bearing as the bar swings inwardly more at the bottom than it moves out at the top under wear and service conditions. In such cases, the substantially horizontal position of the upper portion of the bearing is particularly effective in maintaining a tight pinching fit at this point. Without this provision for a close fit, there is a tendency with some forms of upper bearings toward a pulling away of this upper portion of the bar from the under surface of the rail head as the bar swings inwardly at the bottom.

Figure 5 shows an extreme design in which the upper portion of the web is increased gradually upward by a shallow curved surface C, which is extended downwardly also

with the same uniform curvature to its junction with the concave fillet G at the rail foot. The upper portion of the curve forms a very steeply inclined bearing C, which is cut back at the top 12 by an inwardly inclined side face of the rail head. This extreme inclination of the upper bearing is in contrast with the overhanging or laterally projecting upper bearings shown in Figs. 3 and 4, and is a wide departure from the former art where the average inclination is about 14 degrees with the horizontal. A bar with this steep upper bearing and with the usual fishing angle and rail foot below, would rotate inwardly at the bottom and would slip out from under the load at the top; but with a steep lower bearing located on the outer portion of the foot, the result is almost a balanced condition of the bar against the rail, with a slight tendency inward at the top. This would be the action of the bar without the lower member 13 shown as extending under the rail foot. This base member 13 may be used in various combinations with the features of my invention, as a still further means to control the action of the bar against the rail. With designs having this extreme inclination of the upper bearing, the wedging action under load causes a slight yielding of the rail-joint structure due to a slip and recoil movement between the coacting bearing surfaces, which in turn results in wearing the bearings to a solid fit over their full width and complete length during the life of the bar and the rail. Extra bolting capacity to hold the bar up to its work, together with a flexible or yielding design of bar applied to the modern high rail sections, gives a rail-joint of great elasticity which can be designed to give the same deflection under load as the unbroken rail, this deflection including a slight slipping of the bearings and stretching of the bolts. Excessive wear does not become a factor, since the steep inclination eliminates any limit that there might be to cause removal on account of lack of fit or shortage of metal-allowance for wear during the life of the rail. A friction rail-joint of great flexibility which allows for a resilient frictional movement in its normal action under load and which has no wear limits within the life of the rail, seems to be an entirely new idea in the development of the art and well within the attainment of my invention. A flexible rail-joint of this type maintains tight bolts better than a rigid joint, and solves some of the defects in our modern track practice where the rail-joint acts as a stiff unyielding anvil which causes the rail ends to be punished and battered excessively long before the rest of the rail is worn out.

Figure 6 shows a head bearing somewhat similar to that shown in Fig. 2. The inclination of lower bearing D is also about the same; but it will be noted that in Fig. 2,

this lower bearing is at the inner portion of the foot. This is another good illustration of the effect of the location of the lower bearing, other conditions being similar. The symbol $b-f$ in Fig. 2 shows almost a balanced condition with a slight outward tendency at the top; whereas, in Fig. 6, symbol $f-b$ shows a strong inward tendency at the top. Bearing D is reduced in width almost to a line at the point of tangency of the under face of the bar with the convex upper surface of the rail foot. This upper surface starts in a substantially horizontal position at its juncture with fillet-face G and gradually increases its curvature to its outer edge, where a clearance 14 is afforded between it and the under face of the bar. As the bar swings in at the bottom around its top as a fulcrum, the lower bearing D increases its width by wear toward the outer edge of the rail foot. This outward movement of the bearing as wear takes place, is effective in still further increasing the inward tendency at the top of the bar.

Figures 5 and 6 show another novel advantage of the two-inclination top surface of the rail foot. The lower half of the rail may be made to approach the form of an I-beam, and at the same time, the required amount of inclination for the lower bearing may be obtained so as to give the proper balancing action to the bar. Instead of requiring faces E and G to be built up to the inclination of D, this amount of metal may be used with greater efficiency at a greater distance from the horizontal neutral axis of the rail. This feature is of particular advantage in the modern high-section rails which also require a wide base.

Figure 7 shows a flat upper bearing C of large area, and it has an inclination even greater than the curved bearing shown in Fig. 5. The foot of the rail and bearing D is similar to Fig. 5, except that in Fig. 7 the transition from the inclination of D to that of the free face E is curved at 15. Concave fillet-face G is of large radius, which effects a reduction in the width of face E, with the result that the upper surface of the rail foot is substantially convex with two flattened portions at D and E. In this Fig. 7, symbol $f-b$ shows a slight tendency for the top of the bar to move inwardly.

Figure 8 shows a rail with a very thin web, which is increased gradually without abrupt change in section to the under corner of a very wide head, the side face of the rail head being cut back slightly at 16. A deeply curved bearing at the top gives a good anchorage for the bar under the rail head, and the same curvature is used for the lower bearing D. This gives an exact balance in the action of the bar under the pull of the bolts along their centre line $f'-f'$. The bar is symmetrical with reference to this centre line

so that the bottom bearing could be placed at the top. Lower bearing D is concave, and in occupying the inner portion of the rail foot, it combines with face G in forming an enlarged fillet bearing at the juncture of the rail web and foot. The inclination of E is that of the usual practice. If the bar is considered as having a section as shown by dotted lines with a clearance at 17 and a bearing on top of the foot at 18, then it is obvious that, with the usual low inclination of the foot, the bar would become solidly seated against fillet D very quickly, even with the wide and laterally overhanging rail head at the top. Under such conditions, symbol $b-f$ shows the bar to have a strong tendency outward at the top.

The various novel and practical advantages of my invention may be understood from the above description. The upper portion of the rail web is enlarged and spread out so that the web merges gradually with the width of the rail head at its under corners without any abrupt change in section. This provides a better shape to manufacture, and the resulting gradually sloping faces afford a wide diversity of means for improving the form of the splice bar and for increasing the area of its upper bearing against the rail. The under face of the rail head becomes a combination side-face and under-face bearing, which, in conjunction with the novel method for providing a lower bearing on the rail foot, affords an effective means for adjusting the entire action of the bar against the rail. The "two-inclination" characteristic upper surface of the rail foot which may be merged into a continuously curved convex surface, also effects economies in metal distribution by giving to the lower half of the rail the approximate shape of an I-beam, which is particularly desirable with the large modern rails.

I claim:

1. In a rail-joint, a T-rail having gradually and continuously converging faces extending from the under corner of its head to its web, the width of one of said faces being greater than the distance between horizontal planes at the top of the rail and through said under corners, and a splice bar contacting with a portion of said face, said rail having the top surface of one side of its foot comprising an inner face at its juncture with the rail web and two other faces of substantial width differing from each other in inclination, only one of said faces forming a seat for the splice bar.

2. In a rail-joint, a T-rail having the width of its head diminishing gradually and continuously between the upper and the lower edges of faces extending downwardly and inwardly from the under corners of said rail head, the width of one of said faces between its edges being greater than the height of

the upright side face of the rail head, and a splice bar contacting with a portion of said face and with only one of three faces comprising the width of the top surface of one side of the rail foot, each of these faces having a different inclination from the other.

3. In a rail-joint, a T-rail having the width of its head diminishing gradually to the width or thickness of its web throughout the entire height of a zone included between faces extending from the under corners of said head downwardly and inwardly a diagonal distance greater than the distance between horizontal planes at the top of the rail and through said under corners, and a splice bar contacting with a portion of one of said faces, said rail having the top surface of one side of its foot changed in its inclination adjacent to the mid-point of its width, said splice bar contacting with the rail foot only on one of said inclinations.

4. In a rail-joint, a T-rail having the width of its head reduced to the width or thickness of its web without abrupt changes in the width of its contiguous horizontal sections within the full height of the zone included between faces extending downwardly and inwardly a diagonal distance greater than the height of the upright side face of the rail head, and a splice bar contacting with a portion of one of said faces and with the top surface of one side of the rail foot only on one side of a point in the width of said surface where its inclination changes.

35 5. In a rail-joint, a T-rail having a face extending without abrupt change in direction from the under corner of its head downwardly and inwardly a diagonal distance greater than the height of the upright side face of the rail head, and a splice bar contacting with a portion of said face and with the top surface of one side of the rail foot only on one side of a point in the width of said surface where its inclination changes.

45 6. In a rail-joint, a T-rail having a face extending from the under corner of its head gradually downwardly and inwardly to the rail web, the vertical downward extent of said face being greater than one-half the diagonal distance between the upper and the lower edges of said face, and a splice bar contacting with a portion of said face, said rail having the top surface of one side of its foot comprising an inner face at its juncture with the rail web and two other inclined faces of substantial width differing from each other in inclination, only one of said faces contacting with the splice bar.

7. In a rail-joint, a T-rail having a face extending gradually downwardly and inwardly without abrupt change in direction from the under corner of its head to the upright face of the web, the width of said face being greater than one-half the width of the rail head, and a splice bar contacting with a

portion of said face, said rail having the top surface of one side of its foot comprising an inner fillet face and at least two other faces differing from said fillet face and from each other in inclination, only one of said faces forming a seat for the splice bar.

8. In a rail-joint, a T-rail having a face extending gradually and continuously in a downwardly and inwardly direction from the under corner of its head and comprising a width of face greater than the height of the upright side face of said head, and a splice bar contacting with a portion of said face and having a bearing on the top surface of the rail foot at an inclination greater than another portion of said surface from which said bar stands free.

9. In a rail-joint, a T-rail having an under face of its head comprising a width of face greater than one-half the width of the rail head, and a splice bar contacting with a portion of said face and having a bearing on the top surface of the rail foot at an inclination greater than another portion of said surface from which said bar stands free.

10. In a rail-joint, a T-rail having an under face of its head comprising a width of face greater than the distance between horizontal planes at the upper edge of said face and at the top of the rail, and a splice bar contacting with a portion of said face and having a bearing on the top surface of the rail foot at an inclination greater than another portion of said surface from which said bar stands free.

11. In a rail-joint, a T-rail having an under face of its head disposed so that the distance between horizontal planes at the upper and lower edges of said face is greater than one-half the diagonal distance between said edges, and a splice bar standing free from a portion of the rail web and contacting with a portion of said face and having a bearing on the top surface of the rail foot at an inclination greater than another portion of said surface from which said bar stands free.

12. In a rail-joint, a T-rail having an under face of its head disposed so that the distance between horizontal planes at the upper and lower edges of said face is greater than one-half the diagonal distance between said edges, and a splice bar standing free from a portion of the rail web and contacting with a portion of said face, said rail having the top surface of one side of its foot comprising an inner web-fillet face and two other faces of substantial width differing from it and from each other in inclination, only one of said faces forming a seat for the splice bar.

13. In a rail-joint, a T-rail having an under face of its head comprising a width of face greater than the distance between horizontal planes at the upper edge of said face and at the top of the rail, and a splice bar contacting with a portion of said face and

with only one of three faces comprising the width of the top surface of one side of the rail foot, each of these faces having a different inclination from the other.

5 14. In a rail-joint, a T-rail having an under face of its head comprising a width of face greater than one-half the width of said head, and a splice bar contacting with a portion of said face, said rail having the top surface of one side of its foot comprising a web-fillet face and two other faces differing from said fillet head and from each other in inclination, only one of said faces contacting with the splice bar.

15 15. In a rail-joint, a T-rail having an under face of its head comprising a width of face greater than one-half the width of said head, and a splice bar contacting with a portion of said face, the top surface of one side 20 of the rail foot having its inclination changed adjacent to the mid-point of its width, said splice bar contacting with the rail foot only on one of said inclinations.

16. A T-rail having on the upper surface 25 of its foot a protuberant portion lying between the outer upper corner and the inner web-fillet of said foot, and a splice bar contacting outside of said fillet with a portion of said upper surface which lies at an angle to 30 the horizontal.

17. A T-rail having a portion of the upper surface of its foot projecting above a plane which is tangent to the upper outer corner and the inner fillet-face of said foot, and a splice 35 bar contacting outside of said fillet with a portion of said upper surface which lies at an angle to the horizontal.

18. A T-rail having a foot with a substantially convex upper surface disposed between 40 its upper outer corner and its inner web-fillet, and a splice bar contacting outside of said fillet with a portion of said upper surface which lies at an angle to the horizontal.

In testimony whereof, I have signed at 45 Flushing, in the city of New York and the State of New York, this 5th day of May, 1930.

SAMUEL G. THOMSON.
